CLAIM

I claim the ornamental design for the valve with three mounting holes, as shown and described in the drawings.

DESCRIPTION

FIG. 1 is a front perspective view of a valve with three mounting holes in accordance with the new design;

FIG. 2 is a front plan view thereof;

FIG. 3 is a left side view thereof;

FIG. 4 is an upper side view thereof;

FIG. 5 is a right side view thereof; and,

FIG. 6 is a lower side view thereof.

The broken line showings are for illustrative purposes only and form no part of the claimed design.
